UNITED STATES PATENT OFFICE

161,269

NECKTIE

Paul Karp, Los Angeles, Calif.

Application April 28, 1949, Serial No. 2,322

Term of patent 7 years

(Cl. D3—16)

To all whom it may concern:

Be it known that I, Paul Karp, a citizen of the United States and resident of the city of Los Angeles, county of Los Angeles, State of California, have invented a new, original, and ornamental Design for a Necktie, reference being had to the accompanying drawing, forming a part thereof, in which:

Fig. 1 is a plan view of a necktie showing my new design;

Fig. 2 is an enlarged fragmentary face view thereof showing the ornamentation in detail; and

Fig. 3 is an edge view of the portion of the necktie shown in Fig. 2.

I claim:

The ornamental design for a necktie, substantially as shown.

PAUL KARP.
